UNITED STATES PATENT OFFICE.

HENRY A. WISE WOOD, OF NEW YORK, N. Y., ASSIGNOR, BY MESNE ASSIGNMENTS, TO WOOD NEWSPAPER MACHINERY CORPORATION, OF NEW YORK, N. Y., A CORPORATION OF VIRGINIA.

APPARATUS FOR DRYING MATRICES.

1,245,547.

Specification of Letters Patent.

Patented Nov. 6, 1917.

Application filed November 17, 1910. Serial No. 592,796.

To all whom it may concern:

Be it known that I, HENRY A. WISE Wood, a citizen of the United States, residing at New York, in the county of New York and 5 State of New York, have invented a new and useful Apparatus for Drying Matrices, of which the following is a specification.

This invention relates to the drying of stereotype matrices.

10 The principal objects of the invention are to facilitate this operation so as to reduce the delays which ordinarily occur in carrying it out; to provide means whereby considerable space is saved and a great deal of 15 manual labor dispensed with; to provide means whereby the drying operation is made a substantially continuous one and whereby (regardless of the number of forms that are being dried) there will always be a place 20 provided for an in-coming form; to provide a simple and convenient pressure plate movable with the matrix independently of the drying table; and to provide the same with means for holding in place and applying 25 pressure to the matrix, and for attaching the means to the chase; and generally to improve the method of drying matrices.

The invention also involves means whereby instead of a number of fixed drying 30 machines, a single one can be employed having almost any desired capacity, and capable of operating efficiently either with small or large output.

Further objects and advantages of the invention will appear hereinafter.

Reference is to be had to the accompanying drawings in which

Figure 1 is a side view of a machine embodying one form of this invention.

40 Fig. 2 is a plan of a portion thereof.

Fig. 3 is a sectional view of the same on the line 3—3 of Fig. 2.

Fig. 4 is an end view of one of the details of construction.

45 Fig. 5 is a central section view of the same.

Fig. 6 is a plan of a portion of a pressure plate adapted to be used with said machine.

Fig. 7 is a side elevation of the same.

50 Fig. 8 is a sectional on the line 8—8 of Fig. 6.

Fig. 9 is a side view of a simplified form of the invention, and

Fig. 10 is an end elevation thereof.

As is well understood, the process of drying papier-mâché matrices, occasions an important and annoying delay in the production of a newspaper. As it must necessarily intervene between the closing of a type form and the printing of the first paper, it is 60 obvious that it occupies a portion of what is the most valuable time of a newspaper. On account of this, the large newspaper offices must either have many drying presses at hand, or forms must be held back until 65 preceding forms are dried and out of the way. On account of the cost of these drying presses and the space that they occupy, there is a tendency to have too few of them, so 70 that delays constantly occur. By the present invention these defects in the existing system are eliminated, as the process of drying is made substantially continuous so that 75 there is always a waiting drying place for an incoming form, almost regardless of the number that are in the process of being dried.

This result is secured by providing a comparatively long heating surface or drying table and moving the forms along the same 80 during the process of drying either continuously or intermittently, so that as soon as one form has been placed on the table it will be moved along to leave a space for another. Thus the forms are dried while being carried from one place to another.

A highly developed form of the invention is shown in the first eight figures of the drawings.

The drying table 10 is shown as a steam 90 table but can be heated electrically or in any other desired way. It furnishes an extended surface capable of holding a plurality of forms at once. Along this surface the forms are moved, meanwhile being constantly 95 heated, as will appear hereinafter. This drying table preferably is located adjacent to the molding machine (not shown) so that the forms can be removed from the latter, and directly placed on the table at one of its ends. The machine is shown as operated by an electric motor 11 having conducting wires 12 from the source of electric power, and a hand switch 13 is provided for making and breaking the circuit. The motor rotates a 100 shaft 14 in any desired manner. This shaft is provided with a plate 15, having, in this instance, three lugs 16, each adapted to en-

gage the switch 13 and move it to inoperative position. Therefore, when the switch is thrown in by hand, which the operator does after he has placed a form on the table in the position indicated by A, the motor will start and the shaft 14 will rotate one-third of a revolution and then the next lug 16 will engage the switch and stop it. This motion of the shaft causes the form to move to the position B in the following manner.

The shaft 14 is provided with a cam 17 which has three parts, each one occupying a third of its circumference. One of these portions is concentric with the shaft and the other two constitute projections. These projections cause the cam to move the cam roller 18 outwardly from the center and then back to neutral position twice during each complete revolution. It remains stationary during the other third of the revolution. The cam roller 18 is on an arm 19 mounted on a shaft 20 which is provided with a gear segment 21 meshing with a rack 22. This rack slides transversely of the steam table. It has a pusher 23 which engages and pushes the chases which contain the forms across the table. It will be observed that when the first chase is placed on the heating table, and the motor is started, the first projecting portion of the cam 17 will operate to move the pusher out and back and then the shaft will come to rest. This moves this form from position A to position B leaving the space A vacant. When the second form is put in position A, and the motor started again, the second projecting portion of the cam will operate in the same way and then the shaft will again come to rest. This leaves the first two forms in positions B and C with space A vacant. Now when the third form is put in position A the shaft will operate for another third of a revolution without operating the rack 22.

During the first two thirds of a revolution a cam 25 on the shaft 14, has been guiding its roller 26 in a circular part of its cam groove. Now it comes into operation and the roller enters the off-set portion of the cam groove. This causes the roller to move lengthwise of the shaft so as to swing an arm 27 and segmental gear 28. The latter turns a pinion 29 and a shaft 30 with which it is connected by an ordinary pawl 33 and ratchet wheel 34. They are for preventing backward motion of the shaft 30 when the gear segment returns to normal position. Sprocket wheels 31 meshing with operating chains 32 are mounted on this shaft. The to-and-fro motion of the gear segment advances the chains a distance equal to the distance between cross bars 36. This causes hooks 35, which are mounted on the cross bars 36 connecting the chains, to engage the forms and move them bodily from the positions A, B and C. At the end of this motion

the gear segment moves back without operating the sprocket wheels and then for the next two-thirds of a revolution remains motionless. This leaves the spaces A, B and C vacant, and the parts are now in position 76 for receiving the next three forms in the same way. At each subsequent motion of the chain all the forms are advanced along the table until they reach the discharge end. During this time they are being constantly 75 heated and their matrices dried.

It will be seen, therefore, that this operation provides for the drying of a large number of matrices while their forms are being conveyed from the receiving end of the heating table to the discharging end, whence they are removed in any desired way to be treated as is usual in printing plants.

It will be seen, moreover, that the machine can be operated at smaller capacity and 85 that the capacity of a machine, designed in accordance with the principles herein set forth, can be increased by changes which are obvious.

For the purpose of holding the matrices 90 and applying the necessary pressure to insure their proper contact with the form during drying, and at the same time to otherwise facilitate the drying operation, the following devices are provided. As has been 95 said, the matrix M is molded in the usual way by brush or on a molding machine, in contact with the type T and in a chase S. When it is removed from the molding machine the molding blanket is stripped off 100 and a dry blanket-carrying pressure plate 40 is clamped on the form. This pressure plate is provided with a drying blanket 41 on the under side thereof and this may be held in position by latches 42. These latches 105 are preferably mounted on eccentric shafts 43 supported on the pressure plate and operated by means of removable handles 44 which set in sockets 45 in lugs or the like, fixed on the shaft. When these shafts are 110 turned to proper position, the latches are brought upwardly to securely clamp the edges of the blanket. The pressure plate is provided with perforations 46 to facilitate the escape of moisture and with a handle 47 115 by which the pressure plate can be manipulated. When the pressure plate is placed in position on the form, if its own weight is not sufficient to hold it in position and provide the necessary pressure to keep the matrix in close contact with the type during 120 drying, spring hooks 48 or the like are placed in position to hold the plate. These hooks extend under ledges on the edge of the chase. The pressure plate may have 125 ledges or other devices contacting with the sides of the chase to keep the two elements in proper relative position.

It will be understood, of course, that the invention can be carried out in much sim- 130

- pler ways than that just described. One of these is shown in Figs. 9 and 10. In this case the matrix drying table (either steam or electrically heated) is similar to the one shown in the first figures but not as wide. In this case the forms are advanced a predetermined distance under control of the operator, who as above, throws in an electric switch 13 whenever he has placed a form on the table. The motor 11 controlled thereby operates a shaft 50 shown in this instance as below the top of the heating table and provided with sprocket wheels 51 on which run the endless chains 52. One of the sprocket wheels is provided with lugs 53 adapted to throw the switch out a predetermined number of times, as for example, twice, during a complete rotation of the shaft, thus stopping the motor and the rest 20 of the mechanism after a part of a revolution has been completed. It will be seen by this that each time the switch is thrown in, the sprockets will rotate, in this instance one-half of a revolution. Thus the form just 25 placed in position, as well as the other forms ahead of it, will be advanced along a predetermined path a distance equal to one-half the pitch circumference of the sprockets. This is accomplished in this instance 30 in a very simple way by lugs 54 on the sprocket chains engaging pins 55 on the chase and causing them to advance with the chains. The lugs 53 can be carried either by the sprocket wheel or chain, as desired. 35 When it is desired to use a table the width of two forms, it can be constructed in a manner similar to the machine just described, and the alternate forms placed on the near and far sides of the table respectively. The 40 mechanism is then started when two are in their initial positions.
- While I have illustrated and described certain preferred forms of the invention, I am aware that many modifications can be made 45 in the same without departing from the scope of the invention as expressed in the claims. Therefore, I do not wish to be limited to the details of constructions herein shown and described, but what I do claim 50 is:—
1. In a matrix drying device, the combination with means for holding a matrix in contact with its form during drying, of means for moving said form, and means for 55 constantly heating the form during its movement.
  2. In a drying device for matrices, the combination with a drying table having a length sufficient to accommodate a plurality 60 of forms arranged along the surface thereof, of a plurality of matrix holders each adapted to rest on its form upon said table and each being adapted to hold the matrix in contact with the type, said holders and forms 65 being movable along said table.
  3. In a device for drying stereotype matrices, the combination with a heating table, of means for moving matrices under pressure along the table while supported thereon, whereby they will be dried during their motion. 70
  4. In a device for drying matrices, the combination with a heating table, of means for intermittently moving matrices and their forms along the surface thereof, whereby said matrices will be dried during their motion and while at rest on said table. 75
  5. In a device for drying stereotype matrices, the combination with a heating table, of means for simultaneously moving a plurality of matrices with their forms along the surface of said heating table, said table having a surface for supporting each of said forms in position to be engaged by the moving means. 80
  6. In a device of the character described, the combination of a heating table adapted to support forms with matrices thereon, and an endless conveyer having means for engaging said forms and moving them along the surface of the table. 85
  7. In a device of the character described, the combination of a heating table adapted to support forms with matrices thereon, an endless chain conveyer having means for engaging said forms and moving them along the surface of the table, means for operating said conveyer, and means for automatically arresting the movement of the form after it has been moved from the position in which it is deposited on the table. 90
  8. In a device of the character described, the combination of a heating table adapted to support forms with matrices thereon, an endless chain conveyer having means for engaging said forms and moving them along the surface of the table, and means for intermittently operating said conveyer. 105
  9. In a device for drying matrices, the combination with a heating table adapted to support forms with matrices on the surface thereof, of means for moving a form transversely of the table, and means for moving the form longitudinally of the table. 110
  10. In a device for drying matrices, the combination with a heating table adapted to support forms with matrices on the surface thereof, of means for moving a form transversely of the table, and means for thereafter moving it longitudinally of the table from its initial position thereon toward the opposite end thereof. 115
  11. In a device of the character described, the combination with a matrix drying table having near one end a surface for receiving forms having matrices, means for moving a form deposited on that surface transversely of the table, whereby the space for receiving the form is left vacant, and means for thereafter moving longitudinally said form 120
  12. In a device of the character described, the combination with a heating table, of means for moving matrices under pressure along the table while supported thereon, whereby they will be dried during their motion. 125
  13. In a device for drying stereotype matrices, the combination with a heating table, of means for moving matrices under pressure along the table while supported thereon, whereby they will be dried during their motion. 130

and any form in transverse alinement therewith on the table.

12. In a device of the character described, the combination with a heating table, of a reciprocating conveyer for moving a form and matrix transversely of the table, and an endless chain conveyer for thereafter moving the form and matrix longitudinally of the table.

13. In a device of the character described, the combination with a drying table, of an operating shaft, means connected with said shaft for moving a form and matrix transversely of the table, and means connected

15 with said shaft for thereafter moving said form and matrix longitudinally of the table.

14. In a device of the character described, the combination with a drying table, of an operating shaft, two cams thereon, a conveyer connected with and operated by one of said cams for moving forms transversely of the table, and a conveyer connected with and operated by the other cam for moving forms longitudinally of the table.

15. In a device of the character described, the combination with a drying table, of an operating shaft, two cams thereon, a reciprocating conveyer connected with and operated by one of said cams for moving forms

20 transversely of the table, an endless chain conveyer connected with and operated by the other cam for moving forms longitudinally of the table, the cam connected with the transverse conveyer having means for

25 operating the conveyer, and means for keeping the conveyer stationary during different periods of the rotation of said shaft, the

other cam having means for operating the other conveyer and for holding it stationary during different periods of the rotation 40 of said shaft, the operating means of each cam being in position to operate its conveyer while the other cam holds its conveyer stationary.

16. In a device of the character described, 45 the combination of a heating table, a form adapted to be supported thereon, means carried with the form for holding a matrix in contact with the type, a conveyer, and means on the conveyer for engaging the form and moving it along the table.

17. In a device of the character described, the combination of a heating table having a flat surface, a chase having a flat surface adapted to rest on the table and adapted to 55 carry type, a pressure plate supported by said chase for holding a matrix in contact with the type, said chase being adapted to be moved along the surface of the table with the pressure plate thereon.

18. In a device of the character described, the combination with a heating table, of means for holding type movable along said table, and means movable with said holding means for applying pressure to a matrix on 60 the type.

In testimony whereof I have hereunto set my hand, in the presence of two subscribing witnesses.

HENRY A. WISE WOOD.
